UNITED STATES PATENT OFFICE

JOSEPH MATHOUX, OF PARIS, FRANCE, ASSIGNOR TO SOCIETE ANONYME PREMET, OF PARIS, FRANCE, A CORPORATION OF FRANCE

DESIGN FOR A BOTTLE

Application filed February 4, 1931. Serial No. 38,544. Term of patent 7 years.

To all whom it may concern:

Be it known that I, JOSEPH MATHOUX, a citizen of the Republic of France, residing in the city of Paris, France, have invented a new, original, and ornamental Design for a Bottle, of which the following is a specification, reference being had to the accompanying drawing, forming a part thereof.

In the drawing

Fig. 1 is a front view.
Fig. 2 is a side view.
Fig. 3 is a top view thereof.

I claim:

The ornamental design for a bottle, substantially as shown.

JOSEPH MATHOUX.
